(57) CLAIM

The ornamental design for a furniture base, as shown and described.

DESCRIPTION

FIG. 1 is a side-top perspective view of a furniture base showing my new design;

FIG. 2 is a bottom-side perspective view thereof;

FIG. 3 is a rear elevational view thereof;

FIG. 4 is a front elevational view thereof;

FIG. 5 is a right side elevational view thereof;

FIG. 6 is a left side elevational view thereof;

FIG. 7 is a top plan view thereof;

FIG. 8 is a bottom plan view thereof;

FIG. 9 is another side-top perspective view of the furniture base, wherein the tabletop shown in broken lines in FIGS. 1-8 has been removed to better illustrate the interior portions of the upstanding arms of the furniture base; and,

FIG. 10 is another top plan view of the furniture base, wherein the tabletop shown in broken lines has been removed.

The broken lines showing a tabletop depict environment and form no part of the claim. The remainder of the broken lines depict portions of a furniture base and form no part of the claim.
